United States Patent Office

Des. 189,652
Patented Jan. 24, 1961

189,652

DOOR GRILL

Howard C. Zippel, Levittown, N.Y., assignor to Westmoreland Metal Mfg. Co., Philadelphia, Pa., a corporation of Pennsylvania

Filed Dec. 31, 1959, Ser. No. 58,885

Term of patent 3½ years

(Cl. D54—2)

FIG. 2.

FIG. 1.

FIG. 3.

Fig. 1 is a front elevational view of a door grill, showing my new design;

Fig. 2 is a top plan view; and

Fig. 3 is an edge view thereof.

I claim:

The ornamental design for a door grill, as shown.
